(57) **CLAIM**

The ornamental design for a delivery device including pump and cassette, as shown and described.

DESCRIPTION

FIG. 1 is a perspective view of an embodiment of our design for a delivery device including pump and cassette.

FIG. 2 is a front view of the delivery device including pump and cassette of FIG. 1.

FIG. 3 is a rear view of the delivery device including pump and cassette of FIG. 1.

FIG. 4 is a left side view of the delivery device including pump and cassette of FIG. 1.

FIG. 5 is a right side view of the delivery device including pump and cassette of FIG. 1.

FIG. 6 is a top view of the delivery device including pump and cassette of FIG. 1; and,

FIG. 7 is a bottom view of the delivery device including pump and cassette of FIG. 1.

The broken lines shown throughout these figures depict environmental subject matter only and form no part of the claimed design.

1 Claim, 6 Drawing Sheets
